SOUND RESONATING AND AMPLIFYING ATTACHMENT

John P. Truesdell, Barrington, R. I.

Application May 10, 1934, Serial No. 725,004

6 Claims. (Cl. 181—31)

This invention relates to a sound resonating and amplifying attachment for use in connection with radio apparatus, and has for its object to provide, in a manner as hereinafter set forth an attachment of the class referred to so positioned relative to the speaker of the apparatus for increasing the volume and beauty of tone.

Further objects of the invention are to provide, in a manner as hereinafter set forth, an attachment for the purpose referred to, which is simple in its construction, strong, durable, compact, readily installed into the front of the cabinet of the apparatus in juxtaposition to the mouth of the speaker, thoroughly efficient for the purpose intended thereby and comparatively inexpensive.

To the above ends essentially, and to others which may hereinafter appear, the invention consists of such parts, and such combination of parts as fall within the scope of the invention as claimed.

In the drawing:—

Figure 1 is a front elevation of a radio apparatus showing the adaptation therewith of a sound resonating and amplifying attachment in accordance with this invention.

Figure 2 is a fragmentary view, partly in vertical section and in side elevation of the radio apparatus showing the position of one of the units of the attachment with respect to the mouth of the speaker and the sound outlet opening in the front of the cabinet of the apparatus.

Figure 3 is a fragmentary view, in sectional plan of the radio apparatus showing the position of the attachment with respect to the mouth end of the speaker.

Figure 4 is a perspective view showing the form employed of each unit of the attachment.

The cabinet of a radio apparatus is generally indicated at 5 and includes a front wall 6 formed with a circular sound outlet opening 1. The outer part of the wall 8 of opening 1 is rabbeted to form an endless shoulder 9 and an endless ledge 10. The wall 8 rearwardly of and in proximity to shoulder 9 is provided in the lower part with a groove 11, having a rear straight wall and a forwardly inclined top wall terminating at the outer side of shoulder 9. The ends of groove 11 are closed and are arranged below and in proximity to the horizontal median of opening 1.

Anchored to the inner face of the front wall 6, of the cabinet 5 is the flanged mouth end 12 of the speaker 13. The flange on the latter is designated 14. The inner face of speaker 13 at its mouth end registers with the inner portion of the wall 8 of opening 1.

Arranged within the opening 1 is the attachment, and the latter consists of a series of parallel vertically disposed abutting units 16 of a length to extend from the lower portion of to a point between the horizontal median and the top of the opening 1. Each unit 16 is in the form of a tube 17, open at each end and having its ends oppositely beveled as at 18, 19. The bevels at the ends of the tube 17 extend towards each other and provide in connection with the rear portion of the tube tapered rear portions 20, 21 respectively at the upper and lower ends of the tube. The upper edge of the tube extends downwardly and forwardly from said tapered portion 20 with respect to the rabbet on wall 8. The lower edge of the tube extends upwardly and forwardly from said tapered portion 21 with respect to the rabbet on wall 8. The forming of the ends of the tube, in a manner as stated provide for the rear portion of the latter to be of greater length than the front and major part of the sides thereof. The units 16 form a set of resonators which have open ends and their rear parts of a length to extend from within the lower portion of wall 8 to a point spaced from the upper portion of the latter. The number of the resonators of the set is such that the outer sides of the outer resonators of the set will abut diametrically opposed intermediate portions of an anchoring means for the units. The latter are anchored in juxtaposition to and spaced slightly forward from the mouth of speaker 13.

The tapered holding portion 21 of each tube is seated in groove 11. The beveled end edges of the tube extend across and forwardly with respect to the outer side of shoulder 9.

The tubes are anchored to partly extend across opening 1 by a retainer member 22 which binds against the holding portions 21. The member 22 is secured by any suitable means to the front wall 6 and abuts the shoulder 9 and ledge 10. The member 22 is flush with the outer face of front wall 6 and the inner portion of the wall 8. The major portion of the beveled ends of the tubes are spaced from the member 22.

The resonators of the set gradually increase in length from the outer ones of the set to the central one of the set. The outer resonators of the set have their outer sides bear against member 22.

What I claim is:—

1. In a sound resonating and amplifying attachment for radio apparatus, the combination of the front wall of the cabinet of a radio apparatus having a loud speaker, said wall being

formed with a sound emitting opening, the rear of the wall of said opening registering throughout with the inner face of the speaker at the mouth of the latter, said opening being circular,
5 the wall of said opening being provided with an endless rabbet at its outer portion and a groove in the rear part of its lower portion in proximity to said rabbet, and a set of vertically disposed tubular parallel sidewise abutting resonators
10 within and of less height than that of said opening, said resonators at their lower ends seating upon the lower portion of the wall of said opening, open at each end and oppositely beveled at their ends to provide tapered holding portions
15 at the rear of their ends, said holding portions at the lower ends of said resonators corresponding in contour to and seated in said groove, means secured in said rabbet and coacting with said holding portions at the lower ends of the resonators
20 for anchoring the latter to said front wall to extend partly across said opening, the upper beveled ends and the remaining portion of the lower beveled ends of said resonators being spaced from and surrounded by said means, the resonators of said set gradually decreasing in length from the central resonator of the set to the outer resonators of the set, the said outer resonators having their outer sides bearing against said means, and the upper ends of said resonators being flush with each other.
30

2. In a sound resonating and amplifying attachment for a radio apparatus, the combination of the cabinet of a radio apparatus having its front wall provided with a sound emitting opening 35 for registering with the loud speaker of the apparatus, a set of vertically disposed tubular parallel sidewise abutting resonators arranged in said opening, each of said resonators having a part of its lower end secured in the lower portion 40 of the wall of said opening and its remaining part spaced from said lower portion, each of said resonators being open at each end thereof, and the height of said resonators being less than that of said opening and having their upper ends flush 45 with each other.

3. In a sound resonating and amplifying attachment for a radio apparatus, the combination of the cabinet of a radio apparatus having its front wall provided with a sound emitting opening for registering with the loud speaker of the apparatus, a set of vertically disposed tubular parallel sidewise abutting resonators arranged in said opening, said opening being circular, each of said resonators having a part of its lower end anchored in the lower portion of the wall of said opening and its remaining part extending at an upwardly inclination and spaced from the lower portion of said wall, each of said resonators being open at each end and of a length less than the diameter of said opening, said resonators having their upper ends flush with each other, and the outer resonators of said set sidewise abutting diametrically opposed portions of said wall.

65 4. In a sound resonating and amplifying attachment for a radio apparatus, the combination of the cabinet of a radio apparatus having its

front wall provided with a sound emitting opening for registering with the loud speaker of the apparatus, a set of vertically disposed tubular parallel sidewise abutting resonators arranged in said opening, said opening being circular, each of said resonators having a part of its lower end anchored in the lower portion of the wall of said opening and its remaining part extending at an upwardly inclination and spaced from the lower portion of said wall, each of said resonators being open at each end and of a length less than the diameters of said opening, said resonators having their upper ends flush with each other, and the outer resonators of said set sidewise abutting diametrically opposed portions of said wall, the upper ends of said resonators being positioned between the horizontal median of said opening and the top of the latter.

5. In a sound resonating and amplifying attachment for a radio apparatus, the combination of the cabinet of a radio apparatus having its front wall provided with a sound emitting opening for registering with the loud speaker of the apparatus, a set of vertically disposed tubular parallel sidewise abutting resonators arranged in said opening, said opening being circular, each of said resonators having a part of its lower end anchored in the lower portion of the wall of said opening and its remaining part extending at an upwardly inclination and spaced from the lower portion of said wall, each of said resonators being open at each end and of a length less than the diameter of said opening, said resonators having their upper ends flush with each other, and the outer resonators of said set sidewise abutting diametrically opposed portions of said wall, said resonators gradually increasing in height from the central resonator of said set to the outer resonators of said set, and the upper ends of said resonators being positioned between the horizontal median of said opening and the top of the latter.

6. In a sound resonating and amplifying attachment for a radio apparatus, the combination of the cabinet of a radio apparatus having its front wall provided with a sound emitting opening for registering with the loud speaker of the apparatus, a set of vertically disposed tubular sidewise abutting resonators arranged in and spaced from the inner end of said opening, each of said resonators being formed with oppositely beveled end edges, each resonator having its beveled upper edge extending rearwardly at an upward inclination from its front and its lower beveled rearwardly at a downward inclination from its front, the rear part of the lower edge of each resonator being anchored in the lower portion of the wall of said opening and the remaining part of said lower edge being spaced from said portion, said resonators being open at each end, the outer resonators of said set sidewise abutting opposed portions of the wall of said opening, and the upper ends of said resonators being flush with each other and arranged between the horizontal median of said opening and the upper end of the latter 45 50 55 60 65
